UNITED STATES PATENT OFFICE.

GUSTAV HANSEN, OF VICTORIA, BRITISH COLUMBIA, CANADA.

SHIP'S RAT GUARD.

Application filed May 13, 1927, Serial No. 191,065, and in Canada December 16, 1926.

This invention relates to ships' rat guards, such as are necessary to intercept the passage of rats to and from ships by way of the cables or ropes by which they are moored to the shore.

The object of the invention is to provide a rat guard which is more efficient because much more easily positioned and handled than other devices for the same purpose which are now in vogue. The latter being usually clumsy as well as hazardous to secure in position and therefore time wasting when employed.

The device which I have invented consists of a plate more or less rectangular but preferably wedge-shaped, on the center line of and through which is secured right-angularly thereto a saddle-member which straddles the rope or cable. The saddle member is formed of angle iron and depends materially below the rope on which the device is suspended, so that the center of gravity is below it and therefore retains the lighter and wider portion of the device in a vertical position above the rope or cable where it is most needed to debar the passage of the rat.

The dependent portions of the angle irons above named are spaced apart about the width of the cable and the plate cut away between them thus leaving a groove for the cable as the device is slipped over it for use.

To preclude the possibility of the device slipping off the cable, I employ a pivotal and adjustable slide which can be swung back out of the way for the admission of the cable and afterwards brought back into the vertical position blocking the entrance to the slot and locking the cable or rope in within the saddle member where it can be instantly locked by the turning of a cam or other device.

The details of the invention can be better understood by reference to the drawings herewith and forming part of this application, in which

Fig. 1 is a front elevation.

Fig. 2 is a side elevation.

Fig. 3 is a front view with the locking plate swung out to permit the admission of the rope, and

Fig. 4 and Fig. 5 are side and front elevations respectively of the locking attachment.

Taking the drawings in detail and noting

that similar numerals in the different views represent or indicate identical parts, 6 indicates the guard plate which as shown is of wedge shaped outline, this is provided with a loop handle 7 usable also for hanging the device when not in use, 8 indicates the aperture for the cable 9, the latter being straddled by the saddle member 10 formed by the angle iron 11 and to one side of which is secured the eye and ring 12 to which may be secured a lanyard for positioning the device.

A locking plate 13 pivots at 14 in a slot 15 so that it can be swung out of the way as shown in Fig. 3 when the guard is being slipped over the cable or rope as shown in the drawing consists of an eccentric 17 rigidly secured to the bent lever 16 which fulcrums in the upturned plate 18 the latter being integral with the locking plate 13. So that as the lever 16 is turned over through an obtuse angle towards the guard plate 6 the cam is brought into firm contact with the face of the angle iron 11 thus locking the plate 13 against it in any desired vertical position permitted by the slot 15.

From the above description it will be observed that my device can readily be slipped upon a cable at the ship's side and there secured, thence lowered into correct position by a lanyard, and there remain so long as required, whereas in the case of the ordinary cumbersome rat guards these have to be secured upon the cable by lashing thereto at the position required, which is often a troublesome and hazardous job.

It is to be further noted that where two cables are close together the old form of guard cannot efficiently be employed, whereas mine offers no detriment.

Having now declared the nature of my said invention, what I claim and desire to be secured by Letters Patent of the United States, is:

A ship's rat guard comprising, a flat plate of wedge shape having a slot extending from its periphery to a relatively midway position, two U-shaped plates each having a right angularly turned edge, the inner surface of the said U-shaped plates being coincident with the edges of the said slot and the surface adjacent the right angularly turned edge of each plate being adjacent and secured to the face of the said wedge shaped plate on each side thereof and so adapted to

extend the surface bearing on a cable over which the said guard is straddled, a locking plate parallel to and pivoting on first said plate, said locking plate being adapted to close the entrance to the said slot, said locking plate having a semi-circular recess in its upper extremity corresponding with and op-

posite to a similar recess in the end of the said slot, said locking plate having a slot engaging and adjustable on the pivot above referred to, and locking means whereby the said plate may be secured from movement. 10

GUSTAV HANSEN.
